UNITED STATES PATENT OFFICE

2,012,784

ROAD FINISHING MACHINE

Harry H. Barber, Aurora, Ill., assignor to Barber
Greene Company, Aurora, Ill., a corporation of
Illinois

Application January 3, 1933, Serial No. 649,850

16 Claims. (CL. 94—45)

This invention relates to a road finishing machine primarily designed as a unit for trailing relation with one or more units, but which may be independently used as a finishing machine.

5 It is an object of this invention to provide such a finishing machine or unit which will spread the aggregate consisting of sand, gravel, slag or the like sprayed with a binding agent, evenly over the road bed, tamp the same and smooth the 10 same.

In order to obtain a uniform depth of pavement, a novel control has been provided for the aggregate spreading mechanism. To obtain the desired depth of pavement, the frame for supporting the tampers and finishing screed has been made vertically adjustable and to even up a transversely inclined road bed, the frame is laterally adjustable. This frame is further so supported that it will travel practically unaffected by the 15 uneven or rough condition of the roadway thereby preventing an uneven pavement.

In addition to the features pointed out in the foregoing paragraph, other novel and advantageous features will be pointed out as the description proceeds.

The invention comprises the novel structure and combinations of parts hereinafter described and more particularly pointed out and defined in the appended claims.

In the accompanying drawings which illustrate a preferred form of this invention and in which similar reference numerals refer to similar features in the different views:

Figure 1 is a side elevational view of a road 35 finishing unit involving this invention.

Figure 2 is a front elevational view of the unit or machine.

Figure 3 is a top plan view of the unit or machine.

40 Figure 4 is an enlarged broken and transverse sectional view of the machine showing parts in elevation taken upon the line IV—IV of Figure 3.

Figure 5 is an enlarged fragmentary sectional view taken upon the line V—V of Figure 4 looking in the direction of the arrows.

45 Figure 6 is an enlarged fragmentary sectional view taken upon the line VI—VI of Figure 4 looking in the direction of the arrows.

Figure 7 is an enlarged fragmentary sectional view taken upon the line VII—VII of Figure 4 looking in the direction of the arrows.

50 Figure 8 is an enlarged sectional view taken upon the line VIII—VIII of Figure 4 looking in the direction of the arrows.

Figure 9 is an enlarged sectional view showing

parts in elevation taken upon the line IX—IX of Figure 4 and looking in the direction of the arrows.

Figure 10 is an enlarged fragmentary sectional view with parts in elevation taken upon the line X—X of Figure 4 looking in the direction of the arrows.

Figure 11 is an enlarged fragmentary sectional view taken upon the line XI—XI of Figure 4 looking in the direction of the arrows.

Figure 12 is a side elevational view of one of the crawlers with the frame supporting mechanism shown in section and with parts omitted.

Figures 13 and 14 are diagrammatic views of the unit illustrating the action in passing over 15 level or rough and uneven ground.

Figure 15 is a diagrammatic view of the driving mechanism for operating the unit and the mechanisms thereon.

Figure 16 is an enlarged part sectional and part 20 elevational view of the grade indicator.

Figure 17 is a fragmentary elevational view of the machine illustrating certain features of construction.

Figure 18 is a diagrammatic plan view of the 25 cable control for the adjustable frame of the machine, and the spiral spreaders.

Figure 19 is a diagrammatic view of the control for the aggregate spreading mechanism.

Figure 20 is a diagrammatic elevational view of 30 the cable control for the adjustable frame of the machine.

Figure 21 is a fragmentary side elevational view of a modified form of a feature of the invention.

Figure 22 is a fragmentary side elevational view 35 of a further modified form of a feature of the invention.

Figure 23 is an enlarged fragmentary top plan view of the frame.

Figure 24 is an enlarged transverse sectional 40 view with parts in elevation.

Figure 25 is an enlarged fragmentary elevational view of the center bearing for the spirals.

Figure 26 is an enlarged view taken upon the line XXVI—XXVI of Figure 23.

Figure 27 is a top plan view of a truck propelling means.

In describing the invention with reference to the drawings, it will be noted that the finishing machine or unit comprises a pair of crawlers 1 (Figs. 50 1, 3 and 12). Each crawler carries a beam 2 of

channel formation, and an extension 3, best shown in Figure 1, extends from each end of each beam 2. Near the medial point of each beam 2, there is a bearing 4 (Figure 12) through which a bear-

45

50

55

ing pin 5 projects. Two pairs of parallel and oppositely extending arms 6 are pivoted upon the projecting ends of the pins 5. Each arm comprises a pair of parallel members 6a which are connected by a plate 7 and lattice work 8 (Fig. 3). Each pair of parallel members 6a has a relatively long shoe 9 pivoted to their outer end, that is adapted to travel upon the road side at the edge of the paving. As each pair of parallel members 10 are rigidly connected, each such pair of members may be termed an arm or lever.

With reference to Figure 12, it will be noted that upright channel members 10 are attached to the extensions 3 on the beams 2. These uprights 10 extend between the members 6a and have rotatably anchored thereto at their upper ends screw rods 11 each of which is provided with a hand wheel 12 (Figs. 3 and 12). The lower portions of the screw rods are threaded in nuts 13 (Fig. 12). Each nut 13 is fastened to a pair of upright angle members 14 (Fig. 23) secured to a plate 14a attached to angle members 14b on the parallel members of the arms 6. Thus it will be noted that the screws 11 are rotatably anchored to a stationary part of the machine and are threaded to the shoe supporting arms 6. Consequently, by rotating the screws 11 by the hand wheels 12, the arms and shoes may be raised or lowered with respect to the ground. In traveling from place to place, it is, therefore, possible to raise the shoes above the ground.

The main frame of the finishing unit is supported upon the arms 6, and as these arms 6 are very little affected by hilly or uneven ground due to the shoes 9, such frame will maintain substantially a constant elevation. To this end, each rear arm 6 is provided with a pair of upstanding angle members 15 which are pivoted thereto as indicated at 16 (Fig. 24). In order to support the pivoted angle 15, the arms 6 are preferably provided with plates 17. A channel member 18 is connected to the angles 15 and forms the rear transverse frame member.

Upon each forward arm 6, there is rigidly secured an upright support generally denoted by the reference 19. A pulley 22 is maintained upon each support 19. A cable 21 is trained over the pulley 22 and over a pulley 20 mounted upon a support 23 attached to a forward transverse frame member 24. In referring to Fig. 23, it will be noted that the support 23 includes an angle member 23a rigidly attached to the frame member 24 in order to provide a firm support for the pulley.

The transverse frame members 18 and 24 have longitudinally extending frame members 25 connected thereto. The frame member 25 preferably consists of channel members back to back as shown more clearly in Fig. 4. The rear ends of the channel members 25 are secured to the bottom of the channel beam 18 as shown in Fig. 24, while the forward portions thereof are welded or secured to the supports 23 and the channel members 24. With reference to Fig. 23, it will be noted that one channel 25 of each pair terminates at the frame member 24, while the other channel member of each pair extends past the end of the frame member 24. The frame members 18 and 24 are further braced and connected by a pair of central frame members 26 (Fig. 3) in the form of channel bars and by intermediate channel frame members 27. The frame just described in connection with a lower trussing structure (not shown) constitutes the support for the tamers, the screeds, the driving mechanism and engine. As this frame is pivoted at its rear points upon the

pivots 16 and is adjustably suspended at its forward end by the cables 21, it is obvious that the forward end can be raised or lowered for varying the thickness of the pavement to be laid.

A hopper 28 is suitably supported upon the forward frame member 24. It will be noted that this hopper is substantially centrally located and the outlet thereof is in the form of a slot 29 as shown in Fig. 3. This hopper is adapted to receive the road making aggregate after the same has been treated with a binding agent and deposit the same upon the road bed to be spread thereover by a pair of aligned spiral spreading elements 30. Each spiral spreading element comprises a shaft 30a. The outer portion of each shaft is journaled in a bearing 31 (Fig. 2) supported from the forward frame member 24 by a box-like structure 32. The shafts project beyond the bearings 31 for supporting sprocket gears 33 which will later be referred to. The inner adjacent ends of the shafts 30a are journaled in a bearing 34 (Fig. 25) suspended from the frame member 24 by means of a suitable ranger 35. With this arrangement it is possible to operate one spreading element independently of the other, or to disconnect one while the other one is operating. This is exceedingly desirable as it is possible to distribute the aggregate as desired across the road bed.

After the aggregate is distributed and spread across the road bed, it is acted upon by a pair 30 of aligned tampers 36 best shown in Fig. 4. Each tamper consists of a plate 36a upon the lower portion of which there is welded or secured a tamping element or plate 36b, (Fig. 5) which extends slightly below the plate 36a. A metal strip 36c is 35 welded against the front face of the plate 36b to increase the thickness of the tamping element. To the front face of the metal strip 36c there is welded or secured a metal tamping element or strip 36d which is located above the strip 36c to 40 form a stepped tamper. A pair of filler strips 37 are welded or secured to the upper margin of the tamping element 36b and a plate 38 welded or secured over the filler strip 37 and the stepped tamping element 36d forms a longitudinally extending heat chamber 39 in the tamper. In having the tamper with a forward raised or stepped portion 36d, which is above the surface of the finished pavement, it will be appreciated that the aggregate will be tamped a certain amount before the finishing tamping element 36b comes into contact therewith. This construction is especially desirable when coarse gravel is used and sizeable stones are encountered.

The aligned tampers 36 are adapted to be simultaneously elevated by shafts 40 to which they are eccentrically connected. To this end, a pair of pitmen 41 are pivoted to each tamper by means of pivot bolts 42 (Fig. 10). Each pitman 41 has at its upper end, the usual eccentric strap 43 surrounding a suitable eccentric on the shaft 40. These eccentrics are not specifically shown as they are well known in the art. The outer ends of the shafts 40 are journaled upon the adjustable frame and partake of the adjustment thereof. It will be noted that the outer ends of the shafts 40 are journaled in bearings 44 mounted upon the channels 25. The inner ends of the shafts 40 are journaled in bearings 45 (Fig. 9) supported upon two upright screed supporting members 46. The lower ends of the member 46 are bifurcated for receiving the inner ends of the two aligned screeds 47 which are pivoted to such members by pivot pins 48a. It will be noted that each screed is box-like in cross-section and at 75

the inner end there is a section made from a pair of angle members 47a and 47b and a plate member 47c, the combined width of which fits the bifurcation. Beyond the end section, each screed 5 is made somewhat wider as shown in Figure 11, additional filler plate 47d being used with the angle 47b upon the outside thereof. A smoothing plate 48 is attached to the bottom of each screed. The interior of each screed serves as a 10 heating chamber to which the exhaust from the engine is conducted as will later be pointed out.

The outer end of each screed is pivotally supported upon a hanger 49 (Fig. 4) suspended from the channels 25 by means of an angle 50. It will be noted that an angle clip 51 is fastened to the lower end of each hanger, and a pivot pin 52 connects the end of each screed to an angle clip 51. Each screed 47 is also pivotally supported at an intermediate point from a shaft 40 by means of a hanger 53 only one of which is shown. The inner ends of the two aligned screeds are properly held in alignment by a guide member 55 (Fig. 4), the ends of which are bifurcated for receiving the inner ends of the screeds. This guide member is welded or attached to one of the screeds.

The inner ends of the two aligned screeds 47 and the inner ends of the two aligned tampers 36 are adapted to be simultaneously elevated or lowered for varying the crown of the road. To this end, a nut 56 (Fig. 4) is secured in each hanger 46, and a screw rod 57 extends into each hanger which is made hollow for such a purpose, and is threaded into each nut 56, only one of which is shown.

The screw rods 57 are rockably supported by means of trunnions 58 thereon. These trunnions are journalled in a supporting structure which will now be set forth. In referring to Figures 4 and 9, it will be observed that the two screw rods extend through a box-like structure consisting of a pair of angle members 59 which are welded or rigidly secured at their lower portions to angle members 60 and 61 (Figure 9). The angle member 60 is attached to the channel frame members 25 and 26 as shown in Figures 3 and 8, and forms the main support. The angle member 61 is merely a short angle that connects the lower ends of the angle members 59. Short angle members 62 are welded or secured to the angle members 59 to brace the same. The angle members 59 and 62 are connected by plates 63 which are braced by angle members 64 welded thereto. Angle members 65 (Fig. 4) are welded or secured to the lower edges of the plates 63 in spaced parallel relation to the angles 59. The trunnions 58 are journalled in the angles 59 and 65 as shown in Fig. 4.

One of the screw rods 57 is provided with a hand wheel 66, and the two screw rods are connected by sprocket gearing 67 so that upon turning the hand wheel 67 both screw rods will be actuated for raising or lowering the inner ends of the screeds 36 and as the bearings for the inner ends of the shafts 40 are supported upon the members 46 that support the inner ends of the screed, the inner ends of the shafts 40 will be simultaneously raised or lowered for simultaneously raising or lowering the inner ends of the tampers. Thus it will be seen that the screeds and tampers are simultaneously adjusted for varying the crown of the road.

Each screed support 46 is provided with a pair of spaced apertures 68 (Fig. 10) formed in projecting ears 69. A parallel motion arm 70 is connected to each aperture. The free ends of the

arms 70 are pivoted to angle members 71 (Fig. 8) attached to the frame members 26. Plates 72 may be attached to the frame members 26 to form a guideway for the arms 70.

An angle member 73 (Fig. 4) is attached to each angle 59 and the outstanding flange thereof is provided with a slot 74. A link 75 which is pivoted to each inner pitman 41 extends through the slot 74 in the adjacent angle. A short link 76 is connected to the link 75 and to the upper ear 69. These links 75 and 76 serve to guide the tamper in its reciprocating movements.

The screeds and tampers are preferably heated by means of the exhaust of an engine 77 mounted upon the frame of the machine for operating the different working parts. A flexible hose 78 extends from the exhaust of this engine and connects with a pipe 79 that is coupled to a vertical pipe 80. A U-shaped pipe 81 (Fig. 3) extends from the lower end of the vertical pipe 80 and the two branches 82 of the U-shaped pipe connect with the screeds and tampers as shown in Figure 11. In referring to this figure, it will be noted that a branch 82 of said pipe is connected to a hood 83 attached to a screed and communicates with the screed through a port 84. A short pipe 85 extends from the hood 83 and through a slotted plate 86 attached to a tamper. The plate 36a of the tamper is provided with an opening 87 through which the exhaust from the engine may enter from the pipe 85. A coil spring 88 preferably surrounds the shaft 85 and abuts the collar 86 to maintain the parts in proper relation.

In the present embodiment of the invention, the engine 77 is designed to propel the finishing machine. The machine is also adapted to be coupled to another machine by means of the adjustable cables 89 (Fig. 3) which are attached to the forward frame member 24. As the machine advances, considerable strain is put upon the forward shoes 9 and it is desirable to laterally brace the same. For this purpose, a pair of brace members (Figs. 3 and 23) pivotally connect the forward arms 6 with the frame. To this end, a pivot pin 91 is mounted in a slot 92 (Fig. 24) in each arm 6. A cylindrical bearing 93 is mounted upon the pin. A gusset plate 94 is welded or secured to the bearing. A pair of channel members 95 are secured to the gusset plate and pivoted to the frame as indicated at 96. A second brace member 97 is attached to the gusset plate 94. A plate 98 is attached to the brace member 97 and this plate is pivoted as indicated at 100a (Fig. 26) to an angle member 100 forming one side of the box-like structure 32.

In referring to Figure 23, it will be observed that the shaft 5 which connects the arms 6 to the crawler frame, extends inwardly and has a bearing 101 pivotally mounted thereon. A gusset plate 102 is secured to the bearing 101, and brace members 103 and 104 are secured to the gusset plate. The brace members 103 are pivotally connected to an angle 105 secured to the frame, and the brace member 104 is pivotally connected to angle members 106 attached to the frame. It will, of course, be understood that the frame is braced upon both sides as just described. Only the upper portion of the frame structure has been illustrated, since the matter of trussing the same to sustain the necessary load may be accomplished in various ways by known engineering methods.

The crawlers, the tampers and the spiral screws are driven from the engine 77 in a manner that is diagrammatically set forth in Figure 15. The 75

engine is connected to conventional gearing in a change speed gear box 107 (Fig. 3). The gearing in the gear box is geared by sprocket gearing 108 to an idle shaft 109 which is, in turn, connected by sprocket gearing 110 to the main driving shaft 111. The main driving shaft 111 is journalled in suitable bearings upon the frame work and is geared by duplicate sprocket gearing 112 to the two tamper operating shafts 40. The shaft 111 is also geared by sprocket gearing 113 to the gears 33 on the aligned shafts of the spiral spreading elements.

In referring now to Figure 2, it will be observed that this idle shaft 109 is geared by gears 114 and 115 to a shaft 116 that extends into a conventional change speed gear box 117. A shaft 118 extends from the gear box 117 and this shaft is geared by sprocket gearing 119 (Figure 1) to a jack shaft 120 which is journalled in bearings upon the rear part of the frame previously set forth. This jack shaft 120 is geared by sprocket gearing 121 (Figs. 1 and 3) to a gear 122 (Fig. 23) on a sleeve 123 rotatably mounted upon the shaft 5. A small gear 124 integral with said sleeve is geared by a sprocket chain 125 to a gear 126 (Fig. 1) on a shaft 127 having a gear 128 that drives the crawler. Each crawler 1 is similarly driven from the jack shaft 120. It will be noted that the jack shaft 120 has a small gear 129 at each end for an auxiliary drive as will later more fully appear.

It will be noted that the aligned spiral spreading elements are driven from the shaft 111, and in Figures 18 and 19, there is diagrammatically illustrated a control for throwing either of the spiral elements out of operation. To this end, the sprocket gears 130 upon the ends of the shaft 111 that constitute a portion of the sprocket gearing 113 are loosely mounted upon such shafts and are adapted to be clutched thereto by slidable clutch members 131 slidably splined upon said shaft. The gears 130 are, of course, designed to cooperate with the clutch members. The shipper levers 132 for the clutch members 131 may be connected to levers 133 centrally arranged by means of rods 134 so that either spiral element 45 may be thrown out of operation for a short period in the event that the aggregate should accumulate upon one side. By this control, the spreading of the aggregate over the road bed can be readily controlled.

It will be recalled that the rear portion of the main supporting frame is pivoted upon the pivots 16 and that the front portion thereof is adjustably supported by the cables 21 and the pulleys 20. In Figures 18 and 20 there is diagrammatically illustrated suitable mechanism for operating the cables 21 for elevating or lowering the frame according to the desired thickness of pavement and for elevating one side of the frame and lowering the other side when the road is inclined from one side to the other. To this end, one end of each cable 21 is fastened to a pulley 20 and then trained around a pulley 22, and then back over the pulley 20. The cables are then passed over guide rollers 135 and around opposite sides of a double drum 136 which is rotatably supported in a sheave block 137 pivoted to the frame as indicated at 138. The sheave block has an extension 137a in which a screw rod 139 is threaded. This screw rod has a hand wheel 140 whereby it may be operated. One of the cables 21 after being trained around one half of the drum 136 a few times extends to one side of a double winding drum 141 around one side of which it is wound and to which it is

attached. The other cable 21 after being trained one or more times around the other side of the drum 136 is trained over a guide pulley or roller 142. From the guide pulley 142, this cable extends to the winding drum 141 when it is trained around the other side and attached thereto.

The winding drum 141 is driven by a gear 143 attached to the shaft thereof. This gear 143 is driven by a gear 144 secured to a vertical shaft 145 having a hand wheel 146 thereon. By rotating the hand wheel 146 both cables 21 may be simultaneously wound or unwound with respect to the drum 141 for raising or lowering the frame. In the event that the road bed inclines from one side to the other so that the machine is likewise laterally inclined, the hand wheel 140 may be manipulated for turning the sheave block 137 for winding up one cable 21 and unwinding the other for raising the lower side of the frame and lowering the higher side, until the frame is level, making it possible to maintain the top of the pavement level or in a horizontal plane.

Mechanism has been provided for indicating the depth of the pavement at the crown of the road and also the depth of the pavement that is generally being laid. The indicating means for showing the depth of the crown is illustrated in Figure 17 and consists of a scale 147 fastened upon the supporting structure for the shafts 57 and a pointer 148 cooperating therewith. The pointer is pivoted to the supporting structure as indicated at 149. A block 150 is preferably inserted under the pointer to properly space the same from the supporting structure. An arm 151 fastened to the pointer coaxially with the pivot 149 is attached to a vertical rod 152 which in turn is attached to the bearings 45 for one of the shafts 40. Thus as the bearing 45 is elevated or lowered during the crown adjustments of the tamers and screeds, the arm 151 will be swung for moving the pointer.

The mechanism for indicating the general depth of the pavement is shown in Figures 16 and 2, and in referring to these figures, it will be noted that a hanger 153 is welded to the bottom of the frame members 24. A rod 154 is carried by the hanger. A pair of arms 155 are secured upon the rod 154 by means of collars 156 integral with such arms. Each arm 155 has a curved bearing shoe 157 upon its outer end that is adapted to slide upon the road in advance of the pavement that is being laid. The rod 154 carries a pointer 158 and this pointer travels over a scale 159 attached to the frame member 124. A guide strip 160 on the scale acts as a keeper for the pointer. Thus it will be seen that as the frame including the member 24 is raised or lowered, the rod 154 will rotate, and the pointer 158 will swing for indicating the elevation of the frame and the depth of the pavement that is being laid.

This finishing machine may be used in combination with a mixing unit and an aggregate gathering and elevating unit which supply the aggregate. In some instances, the finishing machine has been used independently of such other units. In such latter instances, a truck is used to dump the aggregate into the hopper 28 of the finishing unit as shown in Figure 21. When the finishing machine is designed to be used with a truck, it is provided with an attachment for engaging the truck and moving the same in advance of the machine until the truck 75

is empty. When the truck is empty, it will travel out of the way under its own power and another truck may take its place.

The attachment illustrated for engaging and propelling a truck consists of a plate 161 (Figure 21) attached to the frame member 24. An arm 162 is adjustably pivoted to the plate 161 through a series of apertures 163. The forward portion of the arm 162 is adjustably secured to a plate 164 which in turn is pivoted to a shoe 165 which is designed to travel upon the ground. A bearing 166 is secured to the arm 162 and this bearing has a series of bearing recesses 167 any of which is adapted for receiving one end of a shaft 168 carrying a long roller 169. It will be understood that there is a similar construction upon the other side of the machine as indicated in Figure 27 for supporting the other end of the roller. The roller 169 is adapted for engaging the rear wheels 170 of a truck 171 designed for dumping road building material into the hopper 28 of the finishing machine.

Due to the adjustment of the arm 162 on the plate 161, and due to the adjustment of the shoe 165 with respect to the arm 162, and due to the fact that the roller 169 may be adjusted with respect to the bearings 166, it is possible to bring the roller 169 in proper contacting relation with the rear wheels of different trucks.

As it requires considerable traction to advance the truck ahead of the finishing unit, the rear shoes 9 of the machine may be replaced by crawlers as shown in Figure 22. In this figure, there is shown a crawler 172 similar to the other crawlers and mounted upon a frame 173 to which is journalled a shaft 174 (Figs. 15 and 22) carrying a driven sprocket wheel 175 and a driving sprocket wheel 176 for the crawler chain. In this construction, the arm 177 which consists of channels similar to the arms 6 is made shorter than the arms 6. A shaft 178 is carried by the arms 177 and this shaft 178 carries a sprocket gear 179 geared by sprocket gearing 180 to the gear 129 on the aforementioned shaft 120. The shaft 178 also carries a sprocket wheel 181 which is geared to sprocket wheel 175 by a chain 182. Such a construction provides four crawlers for propelling the machine and affords sufficient traction for advancing a truck ahead of the machine.

During the operation of the machine, the vertical reciprocation of the tampers imparts considerable vibration to the frame which it will be remembered is hinged or pivoted at its rear end and adjustably suspended by cables at its forward end. The tampers naturally strike the pavement with sufficient force to tamp the road bed, and there is a certain amount of reaction. This reaction which produces most of the vibration of the frame causes the screeds to be slightly elevated when the tampers strike the pavement. While this elevation is very slight, it is sufficient to cause the screeds to travel over the top of the tamped pavement without tearing up the pavement or injuring the same.

In the operation of the machine, the sprayed aggregate or road building material is adapted to be supplied to the hopper 28, either from a mixing unit or from a truck, while the machine is advancing. The spiral elements will spread the material transversely over the road bed, and if there should be an accumulation of material in connection with one of the spiral elements, that is upon one side of the crown of the road, such spiral element may temporarily be thrown out of

action to allow the other end to take more of the material.

Of course, during the travel of the machine, the tampers are at work compacting the pavement, and the screeds are sliding over the tamped pavement for smoothing the same. Should a stretch of road that inclines or dips to one side be encountered, the frame may be tilted by operating the hand wheel 140 to bring the same in a horizontal plane for increasing the thickness of the 10 laid pavement upon the slope and making the same level with the top of the slope. By rotating the hand wheel 146 it is also possible to raise or lower the frame to vary the thickness of the 15 pavement.

As the main frame of the machine is supported upon the arms 6 of the shoes 9, it will be evident from an inspection of Figures 13 and 14 that the level of the frame is very little affected when the machine travels over a rough or uneven road. 20 This is due to the fact that the shoes 9 are of sufficient length to span depressed portions in the road without materially affecting the pivot points of the frame. In addition, the pivot points of the frame travel in a smaller arc than the shoes 25 so that any rise or fall of the main frame is diminished.

Usually, one attendant is all that is necessary for controlling the parts of the finishing machine. A suitable platform 183 has been placed upon the 30 frame for such attendant and from which he can readily observe the operation of the spreading spirals and the other operating parts. In actual practice, machines embodying this invention have paved a mile of road a day, and many miles of 35 roads have already been paved, and due to different adjustments possible, the pavements of such roads have been exceedingly level and smooth.

I am aware that many changes may be made 40 and numerous details of construction may be varied through a wide range without departing from the principles of this invention, and I, therefore, do not purpose limiting the patent granted hereon otherwise than is necessitated by the prior 45 art.

I claim as my invention:

1. In a road building machine, a frame, a pair of aligned spiral spreading elements carried by said frame, a pair of aligned tampers rearward 50 of said elements and a screed adapted for up and down movements behind said tampers.

2. In a road building machine, a pair of crawlers, a pair of arms pivoted to each crawler and extending in opposite directions, a supporting 55 frame pivoted to said arms and having means pivotally connected to said arms and to said frame for transmitting lateral thrust between said arms and frame.

3. In a road building machine comprising a 60 pair of crawlers, a pair of arms pivoted to each crawler and extending in opposite directions, a shoe supported by each arm adapted for traveling upon the side of the road bed, a frame supported upon said arms, means for adjusting said frame 65 and road-paving elements carried by said frame.

4. In a road finishing machine, road traveling mechanisms, a frame hinged to said mechanism, cable means for raising and lowering said frame upon its hinges and means for operating 70 said cable for raising one side and lowering the other side of said frame and road paving elements carried by said frame.

5. In a road finishing machine, a frame, road paving elements carried by said frame including a 75

5. tamper and a screed, an engine carried by said frame for operating said elements and means for conveying the exhaust of said engine to said tamper and screed for heating the same.
6. In a road building machine, a pair of aligned tampers, a pair of aligned screeds extending parallel to said tampers, an engine, means for reciprocating said tampers from said engine and means for conveying the exhaust from said engine to said screeds and tampers for heating the same.
7. In a road finishing machine, a vertically adjustable frame, a shaft carried by said frame, a tamper connected to said shaft for vertical movement, a screed extending parallel to said tamper, said screed being supported for vertical vibration during the reciprocating movement of said tamper.
8. In a road finishing machine, a frame, means for supporting said frame for transverse tilting movements with respect to the road, a pair of aligned shafts supported by said frame, a tamper and a screed supported from each shaft, and means for simultaneously raising or lowering the adjacent ends of said tampers and screeds.
9. In a road finishing machine, a pair of crawlers, a pair of oppositely extending arms pivoted to each crawler, a shoe carried by each arm for traveling upon the road, a frame carried by said arms, a pair of aligned shafts supported on said frame, a tamper and a screed suspended from each shaft and means for simultaneously adjusting the adjacent ends of said tampers and screeds.
10. In a road finishing machine, a pair of aligned shafts, a tamper suspended from each shaft, a pair of aligned screeds, means for supporting the outer ends of the screeds, bearings for the adjacent ends of the shafts, hangers for connecting the adjacent ends of the screeds to said bearings and elevating means for simultaneously raising or lowering said hangers and bearings.
11. In a road building machine including a frame, a shaft, a tamper having eccentric connections with said shaft, a screed suspended from said frame adjacent said tamper, the impacts of said tamper imparting an upward movement to said screed.
12. In a road building machine, a tamper, a screed adjacent said tamper, means for supporting said screed and tamper for vertical movements in opposite directions and means for operating said tamper and causing said screed to be moved in directions opposite to said tamper.
13. In a road building machine including a frame, a shaft journaled in said frame, a tamper suspended from said shaft, a screed suspended from said frame and having vertical vibratory motion imparted thereto during the operation of the tamper.
14. In a road finishing machine comprising tamping means and smoothing means, mechanism for spreading the material to be tamped and smoothed, and means for controlling said spreading mechanism for causing a portion thereof to remain idle while another portion is operating for regulating the spreading of the material.
15. In a road finishing machine, a frame mounted for vertical adjustments, a shaft supported by said frame, a tamper suspended from said shaft, a screed suspended from said frame, and means for operating said shaft for elevating said tamper for descending by gravity for producing an impact and causing an upward vibratory movement of said screed.
16. In a road finishing machine, a crawler frame, a second frame supported upon said crawler frame for vertical and transverse adjustments, and means carried by said second frame for acting upon the roadway.

HARRY H. BARBER.
